UNITED STATES PATENT OFFICE.

FERDINAND RUSTANT, OF MANILA, PHILIPPINE ISLANDS.

NON-REFILLABLE BOTTLE.

1,275,760.

Specification of Letters Patent. Patented Aug. 13, 1918.

Application filed July 23, 1917. Serial No. 182,316.

To all whom it may concern:

Be it known that I, FERDINAND RUSTANT, a citizen of the Republic of France, residing at Manila, in the Province of Luzon, Philippine Islands, have invented certain new and useful Improvements in Non-Refillable Bottles, of which the following is a specification, reference being had therein to the accompanying drawing.

10 This invention relates to a non-refillable bottle and has for its principal object the production of a construction which consists of a plurality of parts which may be easily inserted into the neck of a bottle adapted to receive the same and will efficiently prevent the bottle from being refilled.

Another object of this invention is in the production of a valve casing which is adapted to receive a ball which ball will allow 20 the contents of the bottle to flow out of the same when the same is tilted, but will prevent fluid from being inserted into the bottle.

Another object of this invention is the production of a stopper provided with a conical shaped central bore which is adapted to support the above-mentioned valve casing.

A still further object of this invention is the production of a stopper which may be 30 readily inserted into the bottle, said stopper being provided with dogs which will engage sockets provided within the neck of the bottle so as to prevent the stopper from being moved unless the neck of the bottle is broken.

With these and other objects in view, this invention consists of certain novel combinations, constructions and arrangements of parts as will be hereinafter fully described 40 and claimed.

In the drawing:—

Figure 1 is a fragmentary side elevation of the bottle, showing the neck thereof in section with the non-refillable parts inserted 45 therein.

Fig. 2 is a section taken on the line 2—2, looking downwardly showing a portion of the body-portion thereof broken away.

Fig. 3 is a side elevation of the valve casing and the pipe connected thereto.

Fig. 4 is a section taken on the line 4—4 of Fig. 3.

Fig. 5 is a section taken on the line 5—5 of Fig. 3.

55 By referring to the drawing by numerals, it will be seen that 1 designates the bottle

which is provided with the neck 2. This neck 2 is provided with the collar 3 which is adapted to receive an ordinary stopper. The neck 2 is provided with the sockets 4, 60 the purpose of which will be hereinafter fully described. By referring to Fig. 1, it will be seen that there is provided within the neck 2 the supporting stopper 5, which stopper 5 is provided with a central longitudinal 65 conical bore 6, which bore 6 is larger at its upper end than at its lower end. This stopper 5 is also provided with a plurality of transverse slots 7 which slots 7 are adapted to receive the dogs 8 which are normally 70 held out of the slots 7 by means of the springs 9. By referring again, especially to Fig. 1, it will be seen that these springs 9 which are situated in the slots 7 are adapted to force the dogs 8 into the sockets 4. From 75 this construction, it will be seen that when the stopper 5 is inserted within the neck of the bottle, the dogs 8 will be forced into the sockets 4 by means of the springs 9, thereby making it impossible to remove the stopper 5 from the neck of the bottle, unless said neck is broken.

The conical bore 6 is adapted to receive the conical shaped valve casing 10. This valve casing 10 is provided at its upper end 85 with a substantially spherical or dome shaped head or top 11 and tapers down at its lower end. Adjacent the lower end of the valve casing 10, there is provided the annular groove 12. Between the groove 12 and 90 the lower end of the valve casing 10, there is provided a plurality of oval-shaped openings 13. Adjacent the spherical shaped head 11, there is provided the outlet pipe 14.

The valve casing 10 is adapted to carry 95 the ball 15 which will act as a valve within said valve casing 10. This valve casing 10 is placed within the conical bore 6 so that the same will be supported by the stopper 5 in order to hold the same either in a ring or 100 solder 16 which is provided within the annular channel 12 from which it will be impossible to remove the valve casing 10 from the supporting stopper 5.

When the elements are assembled as shown 105 in Fig. 1, it will be seen that by tilting the bottle, the contents will enter the openings 13 and flow through the valve casing 10 since the valve ball 15 will be in spherical head 11 and will therefore allow the liquid to flow 110 through the outlet pipe 14. When the bottle is in a vertical position, it will be seen

that it is impossible to refill the same because of the fact that the valve ball 15 will be situated intermediate the end portions of the valve casing 10, which will prevent the liquid from flowing therethrough.

From the above description, it will be seen that a non-refillable bottle has been produced which may be quickly and easily assembled after said bottle has been filled. It will also 10 be seen that when the valve casing 10 is fixedly inserted within the bore 6 and the supporting stopper 5 is placed within the neck of the bottle so that the dogs 8 will be sprung into the sockets, that it will be impossible to 15 remove these non-refillable parts without breaking the neck of the bottle. It will also be seen that a manufacturer using this device might use the non-refillable parts over again, that is, he may remove the same by 20 destroying the bottle and could insert these non-refillable elements within a light constructed bottle. This invention is adapted to be constructed of glass with the exception of the springs 9 and of course, solder 16, but 25 I do not wish to limit myself to any specific

material but only to the construction set forth in the pending claim.

What is claimed is:

In a device of the class described, the combination with a bottle provided with a neck, 30 of a supporting stopper inserted in said neck, means for holding said stopper in said neck, said stopper provided with a vertical, conical-shaped bore, a conical-shaped valve casing having a closed dome-shaped top in 35 said conical-shaped bore of said stopper, said valve casing provided with a closed bottom and with an annular groove near the lower end thereof, said casing provided with a plurality of oval-shaped openings formed 40 in its side above the bottom and below the annular groove, a curved outlet pipe integral with the side of said casing contiguous to the dome-shaped top, a solder in said annular groove and bearing against the bottom 45 face of said stopper, and a ball-valve in said casing.

In testimony whereof I hereunto affix my signature.

FERDINAND RUSTANT.
